UNITED STATES PATENT OFFICE.

ABNER D. THOMAS, OF LITTLE ROCK, ARKANSAS.

COTTON-GIN.

SPECIFICATION forming part of Letters Patent No. 682,685, dated September 5, 1899.

Application filed June 12, 1896. Serial No. 595,308. (No model.)

To all whom it may concern:

Be it known that I, ABNER D. THOMAS, a citizen of the United States, residing at Little Rock, in the county of Pulaski and State of Arkansas, have made certain new and useful Improvements in Cotton-Gins, of which the following is a specification.

My improvements in gins have for their chief objects, first, to provide improved means for removing the lint from the saws or other devices used to remove it from the seed; second, to provide improved means for separating the lint from the motes, dirt, and other impurities mixed therewith, and, third, to economize power. I attain these objects by mechanism whose preferred forms are illustrated in the accompanying drawings, in which—

Figure 1 is in part a vertical longitudinal section of the preferred form of my improved gin on line 1 1, Fig. 2, and in part a side elevation of the condenser connected therewith, with the sides partly broken away, so as to show a fan located beneath the condenser.

Fig. 2 is a front elevation of the same apparatus with the gin breast and ribs removed.

Fig. 3 is a detailed inverted plan view, on an enlarged scale, of a section of an air-chamber, hereinafter described, and illustrates the preferable positions of the saws with reference to openings therein. Fig. 4 is an enlarged detail view of a vertical section on line 4 4, Fig. 3.

Fig. 5 is a vertical cross-section, on a reduced scale, on line 5 5, Fig. 1. Fig. 6 is a detailed inverted plan view, on a reduced scale, corresponding to Fig. 3, of a modification in which a continuous slot is substituted for a series of openings. Fig. 7 is in part a vertical longitudinal section on line 7 7, Fig. 8, and in part a side elevation of a modification in which the means for creating the cross-current is a fan located in the flue leading to the condenser; and Fig. 8 is a vertical cross-section on line 8 8, Fig. 7.

Similar numerals refer to similar parts throughout the several views.

The breast 1, seed-board 2, upper circle 3, ribs 4, gin-cylinder 5, its shaft 6, the shaft-bearings 7 7 and 8 8, the pulleys 9 and 10, and the gin-saws 11 are of ordinary construction and are shown arranged in a manner which is not novel.

12 represents the supporting-frame of the gin.

13 represents a fan or blower which may be

located at one side of the gin. Its shaft 14 55 preferably carries a pulley 15, and the fan is preferably driven by means of a belt 16, passing over pulleys 10 and 15 and transmitting motion from the gin-cylinder shaft 6 to the blower-shaft 14. The cylinder-shaft preferably receives its motion through the pulley 9.

17 represents an air-chamber preferably arranged back of the gin-saws 11, substantially as shown in Fig. 1; but that precise arrangement is not essential. It is preferably connected with the fan 13, from which it receives its supply of air, preferably through a pipe 18. The function of the chamber 17 is to distribute the air received through the pipe 18, so as to supply each saw-blade with a 70 blast adapted to blow the lint from its teeth. To that end the bottom 20 of the chamber 18 is preferably pierced at or near the front corner of the chamber by a series of holes 21, one for each saw, preferably vertical, and 75 each preferably arranged with its center directly above the space occupied by each tooth of its saw as such tooth passes down through the horizontal plane in which the axis of the shaft 6 lies. As will be obvious, however, this 80 exact arrangement is not essential in practice, and instead of a series of holes a continuous slot, such as is shown in Fig. 6, in which it is numbered 22, may be used and good though inferior results secured. The 85 arrangement shown in Figs. 1, 2, 3, and 4 is considered best, because it enables power to be economized and the force of the blasts to be directed to the points where it is needed, instead of being to a large extent dissipated 90 and lost.

The air-chamber 17 may be made rectangular, as shown, and where so formed the lower forward corner is preferably beveled at 23, so as to enable it to approach close to the 95 saws. A flue 24 extends back to the condenser 25, which, with the exception of the means for creating a suction of air through it, (hereinafter described,) is of the usual construction. The mouth 26 of the flue 24 preferably extends across the gin at the rear of the space occupied by the saws and extends below the level of the saws.

The mote-board 27, which may be termed the "lower lip" of the mouth, preferably occupies the same position occupied by the mote-board in gins in which the lint is removed from the saws by means of brushes. It pref-

erably slides in horizontal guides 28 28 in the usual manner, and the flue 24 preferably extends up therefrom toward the condenser, as usual in ordinary brush-gins. What may be 5 termed the "roof" 29 of the mouth 26 preferably extends from the bottom of the chamber 17 back of the holes 21, and preferably from a line close behind the holes 21, downward and backward on a curve, to the throat 10 of the flue 24.

Below the saws and in front of the mote-board the gin is preferably open for the admission of air to the mouth of the flue 24 and so as to permit motes, dirt, and other impurities to drop down in front of and below the mote-board, as they do in ordinary saw-gins in which brushes are used.

The ends of the condenser-cylinder 25 are preferably connected by means of pipes or 20 flues 31 31 with a suction-fan 32 of ordinary construction or other suitable means of creating a suction. I prefer to use a separate fan for the condenser instead of creating both the blast and suction by a single fan, because it 25 is desirable to use clean air for the blast, though, as will be obvious, a single fan could be used without departing from the essence of my invention when viewed broadly.

The mode of operation of the described 30 form of my improved gin is as follows: The gin-saws separate the lint from the seed and carry it, with the usual admixture of motes, dirt, and other impurities, back between the ribs 4 in the usual manner. The fan 13 generates a blast of air which passes to the chamber 17 through the pipe 18. From the chamber 17 it passes down in the preferred form through the holes 21, which each direct a blast of air upon each tooth of the saw-blade 35 with which it coöperates and upon the lint on such tooth as the tooth and lint thereon pass beneath the hole. As the holes are preferably wider than the thickness of the teeth, the blast strikes not only the top of each 40 tooth subjected thereto, but its sides, and as it is directed to the point where the lint should leave the teeth, and as it preferably exerts its force downward, it is able to strip the lint from the teeth more perfectly than a blast of 45 the same strength could do it in any other way. Another advantage in using a blast or a series of blasts directed downward is that the tendency of such blasts or blast is to drive the motes, dirt, and dust directly downward, 50 so as to cause them to escape in whole or in part in front of the mote-board in the manner usual in ordinary saw-gins where brushes are used.

If nothing were done to prevent it, the lint 55 would escape with the motes and dirt. This is prevented by a cross-current of air preferably, but not necessarily, generated by a suction device, as shown. By a "cross-current" of air I mean a current which crosses the 60 course pursued by the motes after they leave the saws; but it is not absolutely essential that the air of which this current is composed

should be any other than the air used in blowing the lint from the saws. The course of the air used in blowing the lint and the motes 7c and other impurities from the saws may be changed so as to form a cross-current without materially changing the course of the motes, and, as a matter of fact, the course of the current used in blowing the lint from the saws 75 is changed in this way in the apparatus described, though other air is added to it and forms a part of what is in that case the cross-current, and I wish my claims to be read with this explanation in view. In the preferred form of my gin this cross-current is generated by the fan 32, which, being set in motion, sucks air into the flue 24 and through the condenser-cylinder 25.

The air-chamber 17 is preferably arranged 85 close to the saws, and very little air is able to enter between it and the saws; but a large quantity enters below the saws and its course is indicated by arrows in Fig. 1.

The action of the fan 32 tends to deflect 90 the current of air passing downward from the chamber 17, but in the preferred form of my gin does not materially affect it until after it has blown the lint, motes, &c., from the saws. The specific gravity of the motes, dirt, and 95 other impurities enables them to maintain their course notwithstanding the draft created by the fan 32, and they fall through the opening 33 in front of the mote-board. The lint is, however, deflected and tends to hug 100 the roof of the mouth 26 of the flue as it is carried backward toward the throat of the flue 24, and passes, accompanied in some cases with a certain amount of light dust, to the condenser 25. This dust and any light impurities not extracted with the motes is separated from the lint as it passes over the cylinder of the condenser and is sucked down through the condenser-cylinder by means of 105 the fan 32.

In the modification represented in Fig. 6, 110 22 is a continuous slot, shown as a substitute for a series of openings above the saw-teeth.

In the modification represented in Figs. 7 and 8, the bottom of the flue 24 contains a 115 recess 34, adapted to receive the lower half of a blowing-fan 35 of ordinary construction, whose shaft 36 is shown journaled in bearings 37 37 and having attached to it pulleys 38 and 39, through the former of which it receives motion. Above the fan the flue preferably contains a concave recess 40. In this modification the fan 35 draws air in at the mouth of the flue 24 and forces it through the condenser-cylinder 25 into the side passages 120 41 41 and thence out through the flue 42.

The prior gins of this class with which I am acquainted will not mote satisfactorily. Practical tests of my improved gin have demonstrated that it is capable of doing its work 130 perfectly.

As will be obvious, the forms of mechanism represented in my drawings can be widely departed from without departing from the

substance of my improvements in gins, and I desire to be understood as claiming equivalents broadly. It will also be obvious that the forms of apparatus described are not the only ones which can be used in carrying out my improvements in the art of ginning.

5 I use the words "gin" and "ginning" throughout my specification and claims in a broad sense and include within my meaning, 10 where the former word is used, all machines adapted to remove lint from cotton-seed, and by "ginning" I include removing lint from cotton-seed whether the lint be long or very short.

15 In this specification and throughout my claims I desire to be understood as including within the meaning of the word "impurities" motes, as well as foreign substances, where I speak of the impurities of lint.

20 I claim—

1. In a gin the combination with the rotating means to separate the lint from the seed, of means for directing a current of air across the rotating means to detach the lint and 25 impurities from the rotating means and direct them downward, and means for creating a cross-current of air to cross the path taken by the lint and heavy impurities under the impulse of the first-mentioned current to 30 thereby permit the heavy impurities to continue in their course downward and out of the machine and the lint to be carried by the cross-current of air away from said impurities.

2. In a saw-gin the combination with the 35 saws and means to rotate them of means to direct a current of air tangential to said saws and vertically downward out of the machine, means for creating a cross-current of air to cross the path taken by the lint and heavy 40 impurities under the impulse of the first-mentioned current, to thereby permit the heavy impurities to continue in their course and the lint to be carried by the cross-current away from said impurities.

45 3. In a saw-gin the combination with a flue, the saws and means for operating them, of means for directing a current of air substantially downward and upon the teeth of the saws to detach the lint and impurities 50 therefrom and drive them in a path across the mouth of the flue, and means for creating a cross-current of air to cross the path taken by the lint and impurities under the impulse of the first-mentioned current of air to 55 thereby permit the motes and heavy particles to continue on their course out of the machine and the lint to be carried away by the cross-current.

4. The combination of a series of gin-saws 60 and means for operating them to separate lint-cotton from the seed, a casing, means for directing a current of air substantially downward and upon the saw-teeth to detach the lint and impurities therefrom, an opening in 65 the casing below the saws and to which the current of air is directed, and means for creating a cross-current of air to cross the path

taken by the lint and impurities to thereby carry the lint with said cross-current and permit the impurities to continue on their 70 course out of the machine.

5. In a cotton-gin, a series of saws, a casing, an opening in said casing below the saws, a mote-board adjustable in said opening, means to direct a current of air toward said 75 opening and across the saw-teeth to detach lint and impurities from the saws and direct them downward, and means for creating a cross-current of air to cross the path of the lint and impurities to thereby separate the 80 lint and carry it with said cross-current, and permit the impurities to continue on their course, out of the machine.

6. In a saw-gin the combination of a series of saws and means for operating them, means 85 for directing a blast or blasts of air downward and across the saw-teeth for blowing the lint and impurities mixed therewith from the saw-teeth, a cotton-flue, the roof of which curves upward to form a flue-entrance across 90 which the blast or blasts of air carrying the lint and impurities are directed, an opening in the lower part of said flue for the downward passage of the impurities, and means for creating a cross-blast of air to cross the 95 path of the lint and impurities to separate and carry away the lint and permit the impurities to continue through said opening.

7. In a saw-gin the combination of a series of rotating saws, means for directing a current 100 or currents of air downward and across the saw-teeth for detaching the lint and impurities therefrom, a cotton-flue, the roof of which, curves upward back of the saws, and having an opening below said saws to which the said 105 air-current is directed, an adjustable mote-board forming the lower lip of said opening, and means for creating a cross-current of air to cross the path taken by the lint and heavy 110 impurities to thereby separate and carry away the lint and permit the impurities to continue in their course to the outside of the machine.

8. In a saw-gin the combination of the gin-saws, the air-chamber arranged back of and adjacent thereto, and having air-outlet openings, leading downward, means for forcing a current of air through said openings to detach the lint and impurities from the saws and carry the same downward, the lint-flue, having a mouth 26 across which the air-currents are directed, the mote-board below the saws, an opening in the casing in front of the mote-board and in the path of the said air-currents, and means for creating a cross-current of air to cross the path of the lint and 120 impurities as they are detached from the saws and carried downward to thereby separate the lint and permit the impurities to continue through the said opening.
